**METHOD AND APPARATUS FOR PRODUCING A WELL
THROUGH A PERMAFROST ZONE**

BACKGROUND OF THE INVENTION

Permafrost is defined as a permanently frozen layer at variable depths below the earth's surface in frigid regions. The permafrost layer is composed of frozen soil and rocks that may extend from near the earth's surface to hundreds of feet there below. The upper portions of the permafrost contain intervals of free ice and/or ice lenses. When the ice in the permafrost is melted, the free ice and ice lenses can no longer support the soil and rock, thereby causing downward subsidence of the upper portion of the permafrost. In areas where the permafrost is thick, this upper portion is correspondingly thick and therefore the zone of subsidence on thawing is potentially large.

When a well such as an oil well is drilled through the permafrost layer and produces oil or other liquid through the well bore, the oil or liquid being above the freezing point of water, a substantial amount of permafrost ice can be melted adjacent the well bore over the producing life of the well. Thus, over the producing life of the well a substantial amount of vertical permafrost subsidence can take place.

The well bore is normally lined with a pipe called casing and the casing is fixed to a wellhead structure at the surface of the earth.

When hot oil is produced through the casing in a thick permafrost zone, the ice in the permafrost adjacent the casing is melted along the full length of the casing in the permafrost zone thereby causing settling or subsidence of the upper portion of the permafrost soil and rock downwardly over several hundred feet of the casing in the permafrost zone. As the permafrost soil and rock settle downwardly, it is in frictional or drag contact with the casing and thereby tends to pull the casing with it. Over the producing life of a well, the drag of the subsiding permafrost can reach a magnitude such that the casing is deformed to an extent that it fails and terminates production of the well prematurely.

A layer of cement can be interposed between the casing and the permafrost but this does not prevent melting of the permafrost ice and settling of the permafrost soil and rock, nor does it prevent the casing and cement from being overloaded by the drag forces of the permafrost subsidence to the point of casing failure.

SUMMARY OF THE INVENTION

According to this invention, there is provided a method for producing a well in the earth through a zone of permafrost that is subject to subsidence on thawing of the ice in the permafrost. The method provides, in its improvement, setting the casing in the permafrost zone in contact with and/or exposure to the permafrost and allowing at least one section of this casing to move with the permafrost as it subsides. Thus, one or more sections of the casing moves relative to the remaining casing in the permafrost zone. The movement of casing with the permafrost prevents excessive loading of the casing caused by frictional contact of the casing with the subsiding permafrost soil and rock because the casing moves with and not against the subsiding permafrost.

Also according to this invention, there is provided apparatus wherein the casing in the permafrost zone is set in contact with and/or exposure to the permafrost and this casing carries at least one casing shear element which includes means for allowing at least one section of the casing to move relative to another section and shear means which maintains the movable casing section in a fixed position as set in the well bore until a finite amount of permafrost subsidence has occurred. After the finite amount of permafrost subsidence has occurred, the shear means fails and allows relative movement of the casing sections thereby allowing the casing to move with the permafrost subsidence.

According to this invention the casing is employed in the permafrost subsidence zone substantially without the use of an intermediate cement layer so that substantially all of the casing is employed in direct contact with and/or direct exposure to the permafrost. No attempt is made to isolate or insulate the casing from the permafrost.

Thus, this invention is useful in extending the producing life of a well in geographical areas where permafrost is present and in which fluids at temperatures above the melting point of ice are produced from the well through the permafrost zone to the earth's surface.

Accordingly, it is an object of this invention to provide a new and improved method and apparatus for producing a well through a permafrost zone. It is another object to provide a new and improved method and apparatus for extending the life of a producing well which produces for extended periods through a permafrost zone a fluid which is at a temperature above the freezing point of water. It is another object to provide a new and improved method and apparatus for accommodating permafrost subsidence while producing a well through a permafrost zone.

Other aspects, objects, and advantages of this invention will be apparent to those skilled in the art from this disclosure and the appended claims.

DETAILED DESCRIPTION OF THE INVENTION

The drawing shows a well structure employing this invention.

More specifically, the drawing shows a combination 1 of well casing and wellheads, the casing extending from the earth's surface downwardly in a well bore 2 into a permafrost zone 3 that is subject to subsidence on thawing.

Permafrost zone casing 4 extends into well bore 2 and is directly exposed to the sides of the well bore and therefore to the permafrost 3.

In this invention the term "casing" is meant to cover any pipe or other conduit means which is employed as the liner for the well bore. Therefore, the casing is the outermost pipe in the well bore. The outermost pipe can be made up of two or more separate but concentric lengths of different diameter pipe. All of these pipe lengths are included within the term "casing" in this invention so long as they are the outermost pipe and are in contact with the zone of permafrost subsidence or are immediately adjacent said zone if not in contact therewith. For example, large diameter pipe can be run from the earth's surface down, for example, 500 feet, after which smaller diameter pipe is run down the interior of the larger diameter pipe into a smaller well bore. Both the smaller and larger diameter pipes are included within the term "casing" in this invention as long as both pipes are employed as the outer pipe of the well (through which yet smaller diameter pipes are to be run) and so long as these pipes are the pipes nearest, if not contiguous with, the zone of permafrost subsidence.

For the sake of brevity, the drawing shows only one string of casing for the permafrost subsidence zone so that pipe 5, carried in the interior of casing 4, can be producing casing and/or tubing or other such conduits as required to complete the well but which is not exposed to the zone of permafrost subsidence.

Casing 4 is fixed to its own wellhead 6 while pipe 5 is fixed to a wellhead 7 which is separate from wellhead 6 and which is supported by pipe 5 (pipe 5 is fixed in the wellbore below the permafrost zone in a conventional manner).

When permafrost 3 subsides and moves casing 4 and its wellhead 6 downwardly, wellhead 7 remains fixed in place notwithstanding the movement of wellhead 6. Thus, pipe 5 remains in position as casing 4 moves downward with the permafrost.

Pipe 5 is fixed to wellhead 7 by slip means 8. The slip means are carried in ring 9 and have conventional teeth 10 that bite into the exterior surface of pipe 5. Slip means 8 or other obvious functional equivalents thereof can be employed to prevent upward and/or downward movement of pipe 5. For example,

the upper slip means can have teeth cut at an angle such that they bite into pipe 5 in a direction that prevents pipe 5 from moving downward while the lower slip means can have their teeth cut in the opposite direction so that they bite into the casing in a direction which prevents pipe 5 from moving upward.

Wellhead 7 can carry a plurality of spacer means 11 such as the threaded bolts shown. Bolts 11 can be screwed downwardly through flange 7' of wellhead 7 to come into contact (abutting or threaded) with flange 6' of wellhead 6 after wellhead 6 has moved downwardly with the subsiding permafrost. In this manner contact can be maintained between wellheads 6 and 7 to rigidify the overall wellhead structure notwithstanding physical separation of wellheads 6 and 7 with permafrost subsidence.

Casing 4 is provided with at least one casing shear element 12 which is composed of inner and outer wall members 13 and 14, respectively. While members 13 and 14 are movable upwardly or downwardly relative to one another, they are fixed relative to one another to prevent free movement therebetween by shear means 15. Shear element 12 is initially set in the well bore as shown in the drawing, i.e., with wall members 13 and 14 at a known and preset position which is neither fully open nor fully closed. When the permafrost rock subsidence has occurred for a finite distance thereby imposing an additional load on casing 4 which is sufficient to cause shear means 15 to part or otherwise shear at the interface between the adjacent surfaces of wall members 13 and 14, the section of casing 4 above shear means 15 is free to move downwardly with the subsiding permafrost thereby closing (shortening) shear element 12. It should be noted that it is possible for the sequence of permafrost subsidence to be such that one shear element 12 must lengthen while a lower shear element is shortening to prevent excessive forces on the casing 4.

Shear ring 15 extends into annular grooves in the outer surface of wall member 13 and the inner surface of wall member 14. Other shear devices can be employed. For example, pins, threads, welds, bolts, rivets, and the like can be employed alone or in any desired combination as shear devices.

The shear means can be made by physical design or chemical makeup or both to give any desired strength while setting casing 4 in the well bore thereby preventing parting of casing 4 while it is being handled and set in the well bore. In the same manner, the shear means can be made to part to allow the upper section of casing to subside with the permafrost rock after substantially any finite amount of permafrost subsidence has occurred so long as the drag of subsidence is sufficient to overcome the strength of the shear means built thereinto to withstand handling and emplacement of the casing.

A seal means can be provided between the adjacent faces of walls 13 and 14 such as by O-ring 16 which is seated in an annular groove 17 in the outer surface of inner wall member 13.

Element 12 is threaded at both ends 18 and 19 so that it can be inserted anywhere along the length of casing 4 between two sections of casing that would otherwise be contiguous with one another. Thus, element 12 is insertable in casing string 4 like a normal section of casing.

Since element 12 is emplaceable anywhere along the length of casing 4 between adjacent sections of casing, a plurality of spaced-apart elements 12 can be emplaced along the full length of the zone of subsidence to minimize the drag forces on casing 4 between adjacent shear elements 12. If only a thin zone of permafrost subsidence is anticipated, a single element 12 can be employed. There is no maximum number of elements 12 that can be employed since they can be emplaced in the casing string just like another section of casing and therefore can be emplaced adjacent one another for any length desired.

The method of this invention thereby provides in its improvement setting of at least part of the casing in direct contact with and/or exposure to the permafrost and allowing at least one section of the casing which is in contact with the per-

mafrost to move relative, e.g., downwardly, to the remaining section of the casing in response to permafrost subsidence. This method prevents the casing from experiencing excessive loading due to the permafrost subsiding while in contact with that casing.

Reasonable variations and modifications are possible within the scope of this disclosure without departing from the spirit and scope of this invention.

I claim:

- 10 1. In a method for producing a well in the earth through a zone of permafrost that is subject to subsidence on thawing, the improvement comprising setting a first casing in direct exposure to said permafrost zone, setting a second casing which is inside said first casing and not in direct exposure to said permafrost zone, said second casing being fixed to the earth below the permafrost zone, both casings extending to the earth's surface and each carrying separate and freely separable wellheads, allowing at least one section of said first casing which is exposed to said permafrost zone to move longitudinally relative to the remaining sections of said first casing in response to downward permafrost subsidence thereby preventing said casing from experiencing increased loading due to the permafrost subsiding downwardly while in contact with said casing, and separating said separate wellheads at the earth's surface, the separation being effected by at least one section of the first casing moving downwardly with said permafrost subsidence.
- 20 2. The method according to claim 1 wherein a plurality of spaced-apart sections of said first casing are allowed to move downwardly with the permafrost subsidence.
- 30 3. The method according to claim 1 wherein said at least one movable casing section resists downward movement until a finite amount of permafrost subsidence has first occurred.
- 35 4. In apparatus for producing a well in the earth through a zone of permafrost that is subject to subsidence on thawing, the improvement comprising first casing means set in direct exposure to said permafrost in said permafrost zone, said first casing means being fixed to a first wellhead means, at least one casing shear element carried by said first casing means, said shear element including means for allowing one section of said first casing means to move longitudinally relative to another section of said first casing means, and shear means which maintains said first casing means in the position in which it is set in the earth until a finite amount of downward permafrost subsidence has occurred after which and upon additional permafrost subsidence said shear means fails and allows said relative longitudinal movement of said first casing means section, second casing means inside said first casing means and not set in said permafrost zone, said second casing means being fixed to the earth below the permafrost zone, second wellhead means fixed to said second casing means, said second wellhead means being separate from and unconnected to said first wellhead means, said first and second wellhead means being separable from one another to allow said first wellhead means to move downwardly with the subsiding permafrost while said second wellhead means remains in place.
- 40 5. The apparatus according to claim 4 wherein a plurality of said shear elements are carried at intervals along the length of said first casing means.
- 45 6. The apparatus according to claim 4 wherein said shear element comprises inner and outer wall members which can move upwardly or downwardly relative to one another and which are fixed relative to one another by said shear means so that there is no movement of said wall members relative to one another until said finite amount of permafrost subsidence causes failure of said shear means.
- 50 7. The apparatus according to claim 6 wherein said shear means comprises an annular ring fixed between said inner and outer wall members by grooves in both said inner and outer wall members, said ring extending into the groove in each wall member.
- 55 8. The apparatus according to claim 4 wherein said casing carried by said second wellhead means is restrained from both upward and downward movement by slip means.

9. The apparatus according to claim 4 including movable spacer means for extending between and maintaining physical contact between said first and second wellhead means when spaced apart.

10. The apparatus according to claim 9 wherein said spacer

means comprises at least one screw means carried by said second wellhead means, said screw means being threaded through said second wellhead means into contact with said subsiding first wellhead means.
